APPARATUS AND METHOD FOR THE ELECTROLYTIC PRODUCTION OF METAL HYDROXIDE

Paul S. Roller, 2325 42nd St., NW,
Washington, D.C. 20007

Filed July 12, 1963, Ser. No. 294,677
19 Claims. (Cl. 204—227)

The invention pertains to improvements in the electrolytic production of insoluble metal hydroxides, and more particularly to that of aluminum or iron hydroxide.

Insoluble metal hydroxide can be formed chemically by precipitation, or electrolytically from anodes of the metal in conducting water or aqueous solution. Metals for the purpose include magnesium, zinc, copper, silver, iron and aluminum. At the present time, iron and aluminum are the most important, because their trivalent hydroxides are coagulants, which are applicable to water purification on a wide scale.

In the case of iron anodes, ferrous hydroxide is initially formed, so that oxygen is required, present or provided for, to convert it into the desired trivalent hydroxide.

The electrolytically trivalent hydroxides with their included coagulated impurities may be directly filtered, or may be made to form a floc which is settled before filtration.

Cathodes to said anodes may be of any suitable material. Preferably, the same metal is employed for both anode and cathode, in which instance the electrodes receive reverse, electrolytic current.

According to applicant's U.S. Patent 2,860,090, two metal hydroxide-producing electrodes are employed which are in mutual relation to one another, wherein one electrode is in electrolytic circuit, while the other is alternately out of electrolytic circuit and is being depolarized and readied for reverse current.

Heretofore, assemblages of electrodes have been employed in which the electrode plates have been modified, as by hole drilling, and mutually secured to form a unitary structure. For water treatment purposes particularly, it is desired on the contrary that the electrodes shall be each readily accessible, structurally and electrically.

According to applicant's U.S. Patents 3,006,826 and 2,919,235, a soft gel film is formed on the electrodes during electrolysis. If this film is antecedently removed, the formation of hard deposit or crust on the electrodes is avoided.

One method of removing the film is by wiping of the electrodes. The wiping has to be sufficiently rapid, intrinsically effective and extend over the entire exposed plate in order to obtain satisfactory electrolytic output. Portions of the electrode that are defectively wiped become indurated, and may nucleate various ramifying growths.

Reciprocal linear wiping, as contrasted with rotary wiping, is intrinsically more effective in rejecting wiped matter. However, it has presented more problems in view of a desired close spacing of the electrode plates, their thinning down due to electrolytic consumption, and the demand of complete wiping to a confronting electrode edge.

In the present invention, the electrode plates are slidably assembled in a plurality of co-planar groups. Wiper assemblies are demountably interposed between said groups, and the wipers thereof are passed reciprocatingly over the member electrode plates and insulating elements of each said co-planar group.

It is an object of the invention to provide for slidable installation or removal of an individual electrode plate in a plurality thereof.

Another object is to provide for a co-planar formation

2

of co-operative electrode plates all of which are served by but one wiper.

A further object is to provide for individual current leads to each electrode plate.

5 Still another object is to provide for shrouding of the current lead contacts from the direct electrolytic current path.

A further object is to provide for maintenance of wiping pressure in the presence of slack caused by thinning of the electrode plates.

10 A still further object is to provide for the practicable wiping of an electrode plate to and beyond the confronting edge thereof.

15 Another object is to provide for re-flexing of a wiper strip into an acute angular posture on its reciprocating, return stroke.

Still another object is to provide for the skimming of accumulated matter from a wiper strip in the course of its normal movement.

20 A further object is to provide for the individual, detachable installation of a wiper assembly between adjacent coplanar electrode groups, and its detachable removal therefrom.

With these and other objects and advantages in mind, 25 as will become more apparent hereinafter, reference is made to the accompanying drawings, in which:

FIG. 1 is a vertical sectional view longitudinally through an electrolytic apparatus according to the invention, showing one form of a wiper assembly between adjacent electrode plates;

25 FIG. 2 is a sectional view taken on line 2—2 of FIG. 1;

FIG. 3 is a side view in elevation of an alternate wiper assembly;

30 FIG. 4 is an enlarged fragmentary sectional view taken on line 4—4 of FIG. 3;

FIG. 5 is a sectional view taken on line 5—5 of FIG. 1 and showing a co-planar group of electrode plates and associated insulating strips;

35 FIG. 6 is an enlarged fragmentary sectional view taken transversely through an alternate co-planar group, illustrating more particularly forms of border, collateral and separator strips thereof;

FIG. 7 is an enlarged fragmentary sectional view of an alternate current lead to an electrode plate;

40 FIG. 8 is a sectional view taken on line 8—8 of FIG. 1 and showing the movable carriage for a wiper reciprocating drive means;

FIG. 9 is an enlarged fragmentary section on line 9—9 of FIG. 8 illustrating a detachable joint between a carriage and the end of a lateral arm of a wiper assembly;

45 FIG. 10 is an enlarged fragmentary section taken on line 10—10 of FIG. 8 illustrating the U-shaped end of a slide-member of a carriage;

FIG. 11 is a view similar to FIG. 8 and showing an alternate carriage, and

50 FIG. 12 is an enlarged fragmentary section on line 12—12 of FIG. 11 illustrating a detachable joint between said carriage and the alternate end of a lateral arm.

In describing the preferred embodiment of the invention illustrated in the drawings, in which similar parts are numbered the same, specific terminology will be employed for the sake of clarity. However, the invention is not to be considered limited to the specific terms selected; rather each specific term will be understood to include all technical equivalents operating in a similar manner to accomplish a similar purpose.

Referring now in detail to the drawings, specifically to FIGS. 1 and 2, the invention comprises a receptacle or tank 10, suitably insulated, adapted to contain conducting water or aqueous liquid, and provided with conduits 11 and 12 on end walls 14, for transfer of liquid through said receptacle. Secured to the inner sides of

lateral walls 13 of said receptacle by screws 17 and nuts 18 over water-tight insulating bushings 19 are two oppositely disposed liners or slabs 21 of rigid insulating material and having in their confronting surfaces a plurality of parallel grooves 22 which are mutually aligned and matching to slidably receive the lateral ends of metal hydroxide-producing electrode plates 24. In lieu of the liners 21, the lateral walls 13 may be formed of insulating material and be provided with the grooves 22. Said grooves extend from and open through the top edges 27 of slabs 21 part-way downward to treads 28 which are spaced above the bottom edges 30 of slabs 21, said treads 28 serving to support the plates 24, or the co-planar groups hereinafter described.

Border strips 25 of insulation material are adjacent the transverse edges of said plates 24, and their lateral ends likewise are slidably situated in the grooves 22. They may be of the same thickness as said plates, or except for the ends in said grooves may be thinner than said plates.

An electrode plate 24 and associated top and bottom border strips 25 comprise one form of a co-planar electrode group, the plurality of which is equal to the plurality of matching grooves 22 in slabs 21. Each said co-planar group is secured in grooves 22 by an insulating bar 31 over the top border strip 25. Bar 31, suitably fastened to slab 21 or wall 13, is of the same width as said slab and is provided with cut-outs 34 in order to clear said channels 29.

Collateral strips 32 are preferably included in a co-planar group and are adjacent to and interior of border strips 25, as shown in FIG. 6. Generally of insulating material, they may be part of, or separate, from said border strips. They are at all times thicker than said border strips, and protrude over them.

A co-planar electrode group in its more general form comprises two metal hydroxide-producing electrode plates 24 and 24', auxiliary electrode plates 35 neighboring said plates 24 and 24', an oxidant-producing electrode plate 37, insulating separator strips 38 between adjacent electrode plates, collateral strips 32, and border strips 25 at top and bottom. Said separator and collateral strips may be contiguous to an electrode plate adjacent thereto, or may be displaced therefrom and include a gap therebetween. Separator strips 38, of plastic or other suitable material, may be of the same thickness as the adjacent electrode plates, or alternatively, except for the ends in grooves 22, may be thicker than said adjacent plates and protrude over them as shown in FIG. 6.

Metal hydroxide-producing plates 24 and 24' comprise a supplementary pair in accordance with my U.S. Patent 2,860,090, while auxiliary plates 37 function co-operatively with said metal hydroxide-producing plates in accordance with my co-pending patent application, Serial No. 177,082, now U.S. Patent No. 3,256,162. Oxidant-producing electrode plates 37 are employed to generate oxygen or chlorine, the oxygen for example in the instance of iron electrodes in the co-planar group, and the chlorine for disinfection. The chlorine is generated in the presence of dissolved sodium chloride in the water. It will be clear that still other kinds of electrode plates may be included in the aforesaid co-planar group for any special purpose as desired.

A plurality of similar bus bars 40 and 40', FIGS. 2 and 5, are situated on opposite sides of receptacle 10 exterior to lateral walls 13, and are insulatingly attached to said receptacle, for example by insulating brackets 41 on walls 14. A pair of bus bars 40 and 40' are provided for each said kind of electrode plate, and are positioned mid-way of the lateral ends of the plurality thereof.

Electrolytic power source 43, which may be an omnibus supply for all said kinds of electrodes, contains provisions for current reversal, switches, and resistances, and may include one or more rectifiers, as required. It is con-

nected to each bus bar 40 by lead 44 and to each bus bar 40' by lead 44'.

Current lead screws 46, issuing from each said bus bar through threaded holes 47 therein, make screw-tight contact with the edges of the said electrode plates in grooves 22. Each said lead screw 46 is insulated from receptacle 10 by liquid-tight fitting 48, which is secured in lateral wall 13 by a nut 49 on said screw.

As shown more particularly in FIG. 7, liquid-tight fitting 48 may suitably comprise an O-ring 50 secured in position by a bushing 51 that is thrusted upon by nut 49 on the current lead screw 46. Current lead screws 46 on bus bar 40 make contact with every other of the electrode plates associated with said bus bar, while said lead screws on bus bar 40' make contact with the alternate of said plates.

An alternate current lead is shown in FIG. 7 and includes a resilient member or spring 54 pressing against the lateral end of an aforesaid electrode plate, such as electrode plate 24 in groove 22, and held in said groove by a screw 53. This screw may be sealed by the liquid tight fitting 48 as previously described, said nut 49 being mounted thereon. The screws 53 may be attached to bus bar 40 or 40' by nuts 56.

A wiper assembly interposed between said co-planar groups of electrode plates and insulating strips, comprises two rubber elements or strips 58 extending transversely across said group, two similarly extending holders 59 respectively therefor, a plurality of resilient supports 60 for each said holder and urging the wiper strip thereof to the respective co-planar group, and support means for said resilient supports. The foregoing assemblies are shown diagrammatically in FIG. 1 wherein the resilient supports 60 are mounted back-to-back on support means comprising a single cross-beam 61. Preferably, however, as best shown in FIGS. 3 and 4, the support means comprises an upper cross-beam 66 and a lower cross-beam 67 and the resilient supports 60 for one wiper assembly is mounted on beam 66 while the supports 60 for the other wiper assembly is mounted on beam 67. Wipers 58 now appertain both to upper cross-beam 66 and lower cross-beam 67, whereby each said wiper with holder 59 therefor lies in a plane separate from the other and occupies the entire space between said co-planar groups.

As best shown in FIG. 4, a wiper strip 58 is held securely in U-shaped holder 59, or may be movably held therein. Each of said plurality of the resilient supports 60 is attached to the respective holder 59 by a screw 62, which passes through holes or oversize slots in rubber strip 58. The resilient supports 60 may be constituted by flat springs as indicated in FIG. 1, but it is preferred that these supports comprise a spring portion 63 and a rigid arm portion 64 secured together by a fastener 65. The rigid arm can be attached to the holder 59 and the spring 63 can be fixed to the respective cross-beam 61, 66 or 67 by a screw 69. In addition to the cross-beams, the support means for resilient supports 60 comprises vertically disposed lateral arms 68 attached to said beams and movable in matching channels 29, and a carriage or frame 70 supporting all said arms 68 for vertical reciprocation.

Reciprocating drive means 72 for said wiper assembly may comprise one or more fluid operated cylinders and appurtenances, and includes a drive or piston rod 73 passing in liquid-tight connection into receptacle 10 through bottom 71 thereof. The carriage 70 may comprise a rectangle framework including two lateral members 75 proximal to lateral walls 13, two end-members 76 proximal to end-walls 14, and a center-member 78. A boss 77 on said center-member 78 receives drive rod 73, for example in a threaded fit. Appendages or tongues 80 on each of the four corners of said framework are movable in guide channels 81 on end-walls 14. The reciprocating movement of the carriage 70 imparted by

drive rod 73, is stabilized by said appendages constrained in channels 81.

The lateral members 75 comprise elongate bars the upper surfaces of which, as best shown in FIG. 9, are channelled to provide upstanding flanges 83 and 84 with a platform 85 therebetween and contiguous with inner flange 84. A groove or base 86 is provided within the channelled upper surface of each bar 75 and below the platform 85, such groove being contiguous with the inner side of the outer flange 83. The flanges 83 and 84 constitute outer and inner stops for a slide-member 87 that reposes on platform 85 and is provided with U-shaped ends 89 that double under the ends of the bar 75 as shown in FIG. 10. When adjacent to outer stop 83, said slide-member may be secured in this position by a pin 90 passing through aligned holes 88, 88' in U-shaped end 89 and platform 85.

Lateral arms 68 are adapted to be detachably engaged in the lateral members 75 of carriage 70. For this purpose, each arm 68 is provided with an L-shaped lower end forming a foot 92 which rests in groove 86 inwardly of outer stop 83. Said foot is retained during wiping by slide-member 87 moved over it, said slide-member being secured as aforesaid by pin 90. All lateral arms 68 of the plurality of wiper assemblies are in this wise retained by the two slide-members 87 of carriage 70.

A wiper assembly may be installed between co-planar groups of electrode plates and insulating strips by pushing downward on upper cross-beam 66, or alternately cross-beam 61, until feet 92 rest on base 86. Slide-members 87 are each thereupon moved over the plurality of feet 92, and pins 90 are dropped into place.

In detachably removing said wiper assembly from between adjacent groups of electrode plates and insulating strips, pins 90 are first lifted out of the aforesaid aligned holes and slide-members 87 are moved toward inner stop 84 to uncover feet 92. Thereupon, by pulling upward on upper cross-beam 66, or alternately lower cross-beam 61, said wiper assembly is withdrawn from between said groups.

Alternately, lateral arms 68' each may be provided with a tapered end 94 above which are situated opposite indents 95 as shown in FIGS. 11 and 12. In this arrangement, the lateral members 75' of carriage 70' are provided with a plurality of blocks 100 mounted on their upper surfaces, each block 100 being aligned with a lateral arm 68. Blocks 100 are notched to conform with taper-end 94, and are provided at their sides 101 with hook springs 102 extending above said blocks. Lateral arm 68' is held in block 100 in virtue of springs 102 being engaged in indents 95. The tension of said springs is sufficiently high for the engagement to withstand the pull of wiping.

A wiper assembly is installed by pushing downward on upper cross-beam 66, or alternately cross-beam 61, whereby taper-ends 94 are entered into blocks 100 obversely to springs 102, which thereupon snap into indents 95. The removal of said wiper assembly is effected by pulling upward on upper cross-beam 66, whereby taper-ends 94 are withdrawn from blocks 100 against the holding tension of springs 102.

During electrolytic metal hydroxide-production, the plurality of wiper assemblies is moved reciprocally by drive means 72 transmitting power to carriage 70 or 70' and its lateral members 75 or 75', arms 68 and cross-beams 66 and 67, or alternately cross-beam 61. Wiper strips 58 connected to said cross-beams are thereby passed over each co-planar group of electrode plates and insulating strips, coming to rest at the end of each reciprocating stroke on a border strip 25.

The advantages of the electrolytic apparatus as hereinabove described are numerous, and provide new and improved marks of performance.

Instead of burdensome pre-assemblies separately of electrode plates 24, 24' or 37, these are individually installable by a sliding fit in grooves 22. Electrolytic residues

of said plates 24 or 24' are easily removed by pushing them out with slideable separator strips 38 as tools.

The provision for each electrode plate 35 being close to an electrode plate 24 or 24' in a co-planar group has 5 processing advantages in accordance with my co-pending patent application, Serial Number 177,082, now U.S. Patent No. 3,256,162.

Wiper assemblies between adjacent co-planar groups are individually and detachably installable and removable, 10 resulting in simplified apparatus assembly and maintenance.

Two wipers 58 and holders 59 are required between adjacent co-planar groups of electrode plates and insulating strips. According to the preferred construction as 15 hereinabove described, no greater space between co-planar groups is necessary than that which will accommodate but one said wiper and holder therefor. As a result, close spacing of said co-planar groups of electrode plates is desirably achieved.

Flat springs 60 when elongated result in substantially 20 constant wiping tension against increasing slack caused by the electrolytic thinning down of electrode plates 24 and 24'. Arms 64 provide a rigid spring substitute, whereby excessively long springs, and buckling thereof, 25 are avoided.

The employment of electrode plates 24, 24', 35 and 37 in a co-planar group permits of but one wiper being required for all said plates, instead of a separate wiper for each of said plates when the assemblies thereof are 30 independent.

Moreover, with such a co-planar group all water flow-through receptacle 10 receives an aliquot of electrolytic metal hydroxide, alternately from electrode plates 24 or 24'. When said plates are, however, in separate groups 35 or assemblies, that fraction of water flowing past the non-functioning alternate plates 24 or 24' disadvantageously receives no metal hydroxide.

A still further benefit of the co-planar group is that 40 oxygen generation from an electrode 37 takes place desirably close to an acceptor iron electrode 24 or 24'.

Each of the electrode plates in a co-planar group is independently provided with an electrode lead contact. Any particular contact may be easily broken by backing away screw 46, or disengaging alternate screw 53 from bus bar 40 or 40'. Each said electrode contact is, moreover, protected from the corrosive effect of the electrolytic current by being shrouded in groove 22. The employment of border strips 25 permits wipers 58 to pass thereto beyond the edge of an adjacent electrode plate 24 or 24', whereby said plates are completely wiped, including the edge thereof. Moreover, the length of wiping stroke does not have to be critically adjusted, in view of the indifferent positioning of wiper 58 on said border strips.

55 Wiper strips 58 are bent acutely toward the surface being wiped. With this inclination, the edges of said wipers do not snag in the interstices between said electrode plates and adjacent separator strips or collateral strips. Such acute presentation is therefore necessary at all times. Accordingly, after completing a particular stroke, wiper strips 58 must re-flex into the required acute position for the return stroke. The re-flexing is assured by the construction as aforesaid. Having come to rest on border strip 25, wiper strip 58 is flipped and automatically 60 re-flexed by collateral strip 32 protruding over said border strip. This effect is augmented by said border strip being relatively thin, that is thinner than an electrode plate, as set forth hereinabove.

Collateral strip 32 and separator strip 38 are each 65 desirably thicker than an electrode plate adjacent thereto, whereby they present an overhanging edge to an advancing wiper strip 58. Such edge serves to skim accumulated matter from said wiper strip, and keep it clean. A gap, as aforesaid, between an electrode plate and said collateral or separator strip avoids that sharp corner between

them when they are contiguous. An accumulation of wiped matter which may occur in such a corner is thereby avoided.

It is to be understood that the form of the invention herewith shown and described is a preferred embodiment. Various changes may be made in shape, size and arrangement of parts without departing from the scope and spirit of the invention as claimed.

Having thus described my invention, I claim:

1. An apparatus for the electrolytic production of insoluble metal hydroxide in aqueous solution, comprising a receptacle, the opposite lateral walls of said receptacle being provided with matching parallel grooves, a plurality of co-planar electrode groups, each group comprising metal hydroxide-producing electrode plates and insulating border strips mounted group by group in said grooves with their lateral ends slidingly disposed therein, means to retain each said group in said grooves, current supply means for said plates, and wiping means to remove a soft gel film from said plates during electrolysis.

2. An apparatus for the electrolytic production of insoluble metal hydroxide in aqueous solution comprising a receptacle, the opposite lateral walls of said receptacle being provided with matching parallel grooves, a plurality of co-planar electrode groups, each group comprising metal hydroxide-producing electrode plates, insulating separator strips therebetween and insulating border strips mounted group by group in said grooves with their lateral ends slidingly disposed therein, means to retain each said group in said grooves, current supply means contacting said plates on their ends within said grooves, and wiping means to remove a soft gel film from said plates during electrolysis.

3. An apparatus for the electrolytic production of insoluble metal hydroxide in aqueous solution comprising a receptacle, the opposite lateral walls of said receptacle being provided with matching parallel grooves, a plurality of co-planar electrode groups each group comprising metal hydroxide-producing electrode plates, insulating separator strips therebetween, insulating border strips, collateral strips adjacent to and interior of said border strips, said collateral strips being thicker than said border strips and protruding thereover, said plates and strips mounted group by group in said grooves with their lateral ends slidingly disposed therein, means to retain each said group in said grooves, current supply means contacting said plates on their ends within said grooves, and wiping means to remove a soft gel film from said plates during electrolysis.

4. An apparatus for the electrolytic production of insoluble metal hydroxide in aqueous solution comprising a receptacle, the opposite lateral walls of said receptacle being provided with matching parallel grooves, a plurality of co-planar electrode groups each group comprising metal hydroxide-producing electrode plates, electrode plates auxiliary thereto, insulating separator strips therebetween and insulating border strips mounted group by group in said grooves with their lateral ends slidingly disposed therein, means to retain each said group in said grooves, current supply means contacting said plates on their ends within said grooves, and wiping means to remove a soft gel film from said plates during electrolysis.

5. An apparatus for the electrolytic production of insoluble metal hydroxide in aqueous solution comprising a receptacle, the opposite lateral walls of said receptacle being provided with matching parallel grooves, a plurality of co-planar electrode groups each group comprising metal hydroxide-producing electrode plates, electrode plates auxiliary thereto, oxidant-producing electrode plates, insulating separator strips between adjacent electrode plates and insulating border strips mounted group by group in said grooves with their lateral ends slidingly disposed therein, means to retain each said group in said grooves, current supply means contacting said plates on their ends within said grooves, and wiping means to remove a soft gel film from said plates during electrolysis.

6. An apparatus for the electrolytic production of insoluble metal hydroxide in aqueous solution comprising a receptacle, the opposite lateral walls of said receptacle being provided with matching parallel grooves, metal hydroxide-producing electrode plates mounted in said grooves with their lateral ends slidingly disposed therein, means to retain said plates in said grooves, current supply means contacting said plates on their ends within said grooves, and wiping means to remove a soft gel film from said plates during electrolysis.

10 7. Claim 2 wherein said separator strips are thicker than the adjacent said electrode plates.

8. Claim 3 wherein said border strips are thinner than said electrode plates.

15 9. Claim 3 wherein said collateral strips are thicker than said electrode plates.

10 10. Claim 1 wherein said current supply means comprises screws contacting said plates at their lateral ends in said grooves.

20 11. Claim 1 wherein said current supply means comprises resilient members mounted in said grooves and contacting said plates at their lateral ends therein.

12. An apparatus for the electrolytic production of insoluble metal hydroxide in aqueous solution, comprising

25 a receptacle, the opposite lateral walls of said receptacle being provided with matching parallel grooves, a plurality of co-planar electrode groups each group comprising metal hydroxide-producing electrode plates and insulating border strips mounted group by group in said grooves with

30 their lateral ends slidingly disposed therein, means to retain each said group in said grooves, current supply means for said plates, wiper strips on each said plate to remove a soft gel film from the surfaces thereof, holders for said wiper strips, resilient supports on said holders

35 directing said wipers to the respective wiped plates, and drive means connected to said resilient supports to move said wipers reciprocatingly across said plates.

13. An apparatus for the electrolytic production of insoluble metal hydroxide in aqueous solution, comprising

40 a receptacle, the opposite lateral walls of said receptacle being provided with matching parallel grooves, a plurality of co-planar electrode groups each group comprising metal hydroxide-producing electrode plates and insulating border strips mounted group by group in said grooves with

45 their lateral ends slidingly disposed therein, means to retain each said group in said grooves, current supply means for said plates, wiper strips on each said plate to remove a soft gel film from the surfaces thereof, holders for said

50 wiper strips, rigid arms connected to said holders, flat spring means attached to said arms directing said wipers to the respective wiped plates, and drive means connected to said spring means to move said wipers reciprocatingly across said plates.

14. An apparatus for the electrolytic production of insoluble metal hydroxide in aqueous solution comprising

55 a receptacle, the opposite lateral walls of said receptacle being provided with matching parallel grooves and matching parallel channels intermediate said grooves, a plurality of co-planar electrode groups each group comprising metal hydroxide-producing electrode plates and insulating border strips mounted group by group in said grooves with

60 their lateral ends slidingly disposed therein, means to retain each said group in said grooves, current supply means for said plates, two wiper strips between opposite

65 said co-planar groups to remove a soft gel film from the respective surfaces thereof, two holders respectively for said wiper strips, flat spring means on said holders directing said wipers to the respective wiped plates, a frame

70 comprising cross-beam means supporting said spring means and lateral arms at the ends of said cross-beam means slidingly movable in said channels, a carriage in said receptacle, the ends of said lateral arms detachably engaged with said carriage, and reciprocating drive means

75 connected to said carriage.

15. Claim 14 wherein the ends of said lateral arms are L-shaped and said framework includes a base supporting said L-shaped ends and a slide-member over said base retaining said L-shaped ends.

16. Claim 14 wherein said lateral arms have a taper-end with indents thereover, and said framework includes notched blocks and hook springs on the sides thereof, said taper-ends being retained in said blocks by said springs secured in said indents.

17. Claim 14 wherein said carriage is provided with a plurality of appendages, and guide-members are mounted on the walls of said receptacle, said appendages being movable in said guide-members.

18. Claim 14 wherein said cross-beam means comprise an upper cross-beam and a lower cross-beam, and said 10 spring means on one said holder is attached to said lower cross-beam and on the other said holder to said upper cross-beam.

10

19. In the electrolytic production of metal hydroxide from electrode plates bordered by insulating strips, passing wipers over the electrode plates beyond the confronting edge thereof to said insulating strips, coming to rest 5 thereon, and then passing the wipers over said plates oppositely and reciprocatingly.
